UNITED STATES PATENT OFFICE

WILLIAM J. CLEMENTS, OF CHICAGO, ILLINOIS, ASSIGNOR TO CLEMENTS MFG. CO., OF CHICAGO, ILLINOIS, A CORPORATION OF ILLINOIS

VACUUM CLEANER

Application filed April 26, 1930. Serial No. 447,579.

My invention relates to an improvement in vacuum cleaners and particularly to an improvement in that type of vacuum cleaner in which a motor and housing therefor are associated with a fan chamber and a fan, there being a suction inlet to said fan chamber and an exhaust outlet therefrom. One object of my invention is the provision of means for securing in rotation a plurality of quickly removable suction inlet nozzles to said fan chamber, the nozzles being of different form and for different purposes, all being readily removable from and detachable in operative relation with the fan chamber. Another object is the provision of a removable nozzle for such a suction cleaner, said nozzle being adapted to receive a supplemental suction inlet, the suction nozzle structure, with or without said supplemental inlet, being removable as a unit from the suction cleaner. Another object is the provision of means for securing selectively to the suction cleaner, a nozzle having a beating or sweeping brush, or a nozzle without such brush. Another object is the provision of means for adjusting the height of the vacuum cleaner to position a floor engaging nozzle adjacent the floor surface, or at any desired height above such surface, within a reasonable range of adjustment. Other objects will appear from time to time in the course of the specification and claims.

I illustrate my invention more or less diagrammatically in the accompanying drawings, wherein—

Figure 1 is a side elevation, with parts in section, illustrating a suction cleaner having secured thereto one of the removable nozzle members;

Figure 2 is a section along the line 2—2 of Figure 1;

Figure 3 is a view similar to Figure 1 showing a different form of nozzle;

Figure 4 is a side elevation with parts in section showing the same nozzle as in Figure 1 with a different fitting inserted in the nozzle and the nozzle in position to be connected to the fan housing; and

Figure 5 is a view illustrating the nozzle

removed with a hose connection fitting in place in the nozzle.

Like parts are indicated by like symbols throughout the specification and drawings.

Referring to the drawings, and initially to Figure 1, A generally indicates any suitable vacuum cleaner member or housing, which may include the motor housing A¹ in which is indicated any suitable motor means shown in Figure 1 in dotted lines as A². The motor is provided with a motor shaft A³ lying preferably but not necessarily along the central axis of the motor housing A¹. The motor housing is herein shown as terminating at one end in the circular flange A⁴, the diameter of which is shown as somewhat exceeding the normal diameter of the housing A¹. Aligned with it is a partition member A⁵ through a central aperture in which extends the inner end of the motor shaft A³.

Secured in any suitable manner to the flange A⁴ is the fan housing or fan chamber member generally indicated as B. It is shown as generally helical in cross-section with an edge B¹ opposed to the flange A⁴. Said flange A⁴ may be provided with screws B², whereby the motor and fan casings may be secured to each other to form an effective operating unit. B³ indicates a peripheral and tangential exhaust passage which may terminate as at B⁴ with any suitable locking flange or member B⁵, whereby the exhaust receiving pervious bag B⁶ may be secured thereto. B⁷ indicates an axial air inlet, herein indicated as having the bevel edge B⁸ adapted to receive one of the suction nozzle members later described. B⁹ is a securing lug structure which includes a pin having the ends B¹⁰. B¹¹ is another locking lug having pivoted thereto the locking lever B¹² with the wedging locking surface B¹³, the purpose of which will later appear.

In order to support the fan and motor housing in any desired normal relation to the floor or surface to be cleaned, I illustrate a rear bracket C formed with a securing extension C¹ which conforms to and may be screwed or otherwise secured to the end of the motor housing A¹, as by the screws C².

Pivoted to the bracket C is any suitable roller or rollers C³. C⁴ C⁴ indicate roller abutment lugs mounted upon or formed upon the exterior surface of the fan housing B. 5 Mounted therein is the rotatable shaft or member C⁵ upon which are the arms C⁶ to which are pivoted the supporting rollers C⁷. C⁸ is another arm upon the shaft C⁵, the arms C⁶ and C⁸ forming together in effect a 10 bell crank lever. C⁹ is an additional lug upon the exterior of the fan housing B, which is screwthreaded to receive the adjusting screw C¹⁰ with its manual control member C¹¹. The inner end of the member C¹⁰ is 15 reduced as at C¹² to penetrate a portion of the arm C⁸, whereby, in response to rotation of the member C¹⁰, said arm may be adjusted to control the angular relation of the arms C⁶. For example a clockwise rotation of 20 the member C¹¹ may depress the outer ends of the arms C⁶ and thus lift the fan housing from the floor. A reverse rotation has the opposite effect, lowering the fan housing in relation to the floor. 25 D indicates any suitable fan within the fan housing B, and mounted upon the motor shaft A³. It may include the central hub D¹, the lateral extension D² therefrom, and a plurality of vanes D³. The result of the rotation of the fan is the expulsion of the exhaust from the passage B³ and a consequent suction through the aperture B⁷. D⁶ indicates a screwthreaded extension of the fan and motor shaft beyond the forward face 30 of the fan hub. It may be screw-threaded to receive a removable shaft extension generally indicated as D⁷, and provided with a belt engaging portion D⁸ properly curved or arculate in cross-section, in order to hold a 35 belt thereupon. 40

In order to permit an employment of the power plant and suction device thus employed which shall be of maximum flexibility and variability in use, I prefer to employ 45 a plurality of separate and individually usable suction nozzles. Since an important feature of my invention is the selective employment of suction nozzles of different type I wish it to be understood that although the 50 suction nozzles in Figure 1 and some of the other figures may differ in detail, I am not illustrating alternative forms of my invention, but rather parts of a single set or unit which includes the main power plant and a 55 plurality of selectively employable suction inlet members.

Referring to the particular member shown in Figure 1, E generally indicates a suction nozzle structure terminating at its lower 60 edge in the laterally extended portion E¹ adapted to be opposed to the surface to be cleaned, and terminating in a lower edge E². E³ are suitable yielding buffers to prevent damage to articles of furniture and the like 65 by contact with the nozzle. The nozzle E¹

is expanded at its upper end into the generally cylindrical connector member E⁴ which may include the forward wall E⁵ and a rear wall E⁶. These two walls are apertured in alignment as at E⁷ E⁸. Extending inwardly beyond the wall E⁶ is a generally cylindrical flange E⁹ with a bevel or chamfered exterior surface E¹⁰ adapted to engage and conform to the opposed inclined surface B⁸, upon the forward wall of the fan chamber B. In order to lock the nozzle in place in relation to the fan housing I provide the lower lugs E¹¹ formed with a hook or terminal portion E¹² conforming to and adapted to hook over the pins B¹⁰. The upper lug or extension E¹³ is adapted to approach the locking lug B¹¹ and may be engaged by the wedge surface B¹³ of the lever B¹². 70 75 80 85 90 95 100 105 110 115 120 125 130

In order to render the nozzle structure E adaptable both for employment upon a floor or for the cleaning of draperies and the like I provide the supplemental hose connecting member generally indicated at G. It includes an extension of reduced diameter, G¹, adapted to be inserted into the end of a hose G². It is provided with a circumferential flange G³, with a packing G⁴, and a cylindrical extension G⁵ adapted to penetrate the aperture E⁷ and snugly engage the edge of the aperture E⁸, as shown in Figure 5. Any suitable means may be employed for holding the hose inlet G in position, for example the wedging member G⁶ opposed to corresponding wedging members G⁷ upon the nozzle structure. It will be seen from Figure 5 that when the hose inlet is in position the normal air inlet through the floor nozzle E¹ is entirely cut off. It will be further observed, from Figure 5 that the nozzle structure may be removed as a unit from the fan housing, regardless of whether or not the hose connection is in position. When the hose connection is not employed, the closure H may be used, which includes the flange H¹ corresponding to the flange G³ of the hose inlet, the packing H², the generally cylindrical portion H⁴ adapted to penetrate the aperture E⁷, and any suitable securing means, for example the locking members H⁵. It will be noted that the size of the parts is such that even though the removable shaft extension D⁷ is in position, the nozzle structure may be freely applied and removed and the hose inlet may also be freely inserted or removed. 120 125 130

When it is desired to employ a different type of nozzle, for example when it is desired to employ a nozzle having a beating brush or sweeping brush or a floor polishing or treating member of any kind, such a nozzle may readily be applied to the fan housing. Referring for example to Figure 4 I generally indicates an elective form of nozzle, with the enlarged lower portion I¹ in which is pivoted any suitable rotary mem-

ber I², having any suitable bristles or floor engaging means I³, which preferably project below the lower edge I⁴ of the portion I¹. I⁵ indicates any suitable driving pulley 5 mounted upon the rotary member and adapted to receive any suitable driving belt I⁶ which is applicable to the removable shaft extension D⁷. Note that the closure H may be employed with the nozzle I and that it 10 is so aligned with the removable shaft extension as to permit ready access to the shaft for insertion or removal, or for the application of the belt I⁶. Note also that the hose connection G may be applied with equal 15 readiness to the nozzle E or to the nozzle I. The adjustment above described permits the raising or lowering of the fan shaft to adjust either form of nozzle in any desired relationship to the surface to be worked 20 upon.

It will be realized that whereas I have described and shown a practical and operative device, nevertheless many changes might be made in the size, shape, number and disposition 25 of parts without departing from the spirit of my invention. I therefore wish my description and drawings to be taken as in a broad sense illustrative and diagrammatic rather than as limiting me to my 30 specific showing.

In particular I may employ my invention either with a vacuum cleaner of the horizontal axis type, or of the vertical axis type.

In actual operation of the device it will 35 be understood that a vacuum cleaner may be supplied having alternative nozzles. Each nozzle may be secured to the fan chamber, as for example by the locking means shown in Figures 1 and 2, including the wedging arm B¹², the pins B¹⁰, etc. The device can thus almost instantaneously be converted 40 from a simple suction device, as shown in Figure 1, to a beater brush type as shown in Figure 4. It will be understood that other 45 types of nozzles may be supplied for a given set, nozzles varying in shape or in size. All of these nozzles are provided for the ready insertion, without removal of the nozzle, of 50 the suction hose inlet, as shown in Figure 5. This inlet member may be applied to the nozzle either when the nozzle is in place, or when it is removed, and for quick substitution 55 of nozzles it is not necessary to remove the hose connection, if it happens to be in the nozzle which is to be removed. Preferably the pulley D⁸ is removably mounted in relation to the fan or to the motor shaft. However, it may be permanently left in 60 position or permanently secured in position without interfering with the insertion and removal of the nozzle or of the suction inlet. Note also that when the device is to be converted from a plain suction machine to a 65 brush machine, the belt may easily be ap-

plied to the pulley D⁸ through the aperture closed by the closure H.

I claim:

1. In a suction cleaner, a pump chamber, having integral front and rear walls, the front wall of said chamber being formed with an air inlet passage therethrough, a nozzle and means for removably securing it in operative relation with said air passage, said nozzle including an inlet portion 70 adapted to be opposed to a surface being cleaned and a connecting portion extending thence for operative connection with the air passage, said connecting portion having aligned openings receiving a connecting inlet tube, one of said openings being in the line of flow of air from the inlet portion to the air passage of the pump chamber, whereby a connection of the tube closes the 75 opening to the inlet portion of the nozzle. 80

2. In a suction cleaner, a pump chamber, having integral front and rear walls, the front wall of said chamber being formed with an air inlet passage therethrough and being beveled, a nozzle structure and means 90 for removably securing it in operative relation with said air passage, said nozzle structure including an inlet portion adapted to be opposed to a surface being cleaned, an abutment member having a beveled portion 95 adapted to engage and to conform to the beveled opening of said air passage and a connecting portion extending between the inlet portion and the abutment member, said connecting portion having aligned 100 openings receiving a connecting inlet tube, said openings being generally aligned with the said air inlet passage, one of said openings being in the line of flow of air from the inlet portion of the nozzle to the pump chamber, whereby a connection of the tube 105 closes said opening to the inlet portion of the nozzle.

3. In a vacuum cleaner nozzle for removable attachment to a fan housing having integral walls, one of which is provided with an inlet opening, an air inlet portion adapted to be opposed to the surface being cleaned and a connecting portion, said connecting portion having aligned openings 110 therein, and a connecting inlet tube disposed in said openings, one of said openings being defined by an annular rib within the connecting portion forming a bearing for one end of the connecting tube. 115

4. In a vacuum cleaner nozzle for removable attachment to a fan housing having integral walls, one of which is provided with an inlet opening, an air inlet portion adapted to be opposed to the surface being cleaned and a connecting portion, said connecting portion having aligned openings 120 therein, a connecting inlet tube disposed in said openings, one of said openings being defined by an annular rib within the connecting 125 tube. 130

necting portion forming a bearing for one end of the connecting tube, the other opening being bounded by a cam surface, and means on the inlet tube engageable with 5 said surface to lock the tube to the nozzle.

Signed at Chicago, county of Cook, and State of Illinois, this 22nd day of April 1930.

WILLIAM J. CLEMENTS.
